CONTAINER CAP

Philip O. Hoag, Newark, N. J., assignor to The
Whitehead & Hoag Company, Newark, N. J., a
corporation of New Jersey

Application May 12, 1933, Serial No. 670,627
Renewed April 23, 1936

5 Claims. (Cl. 40—20)

This invention relates to a novel and improved form of container cap, the novel features of which will be best understood from the following description and the annexed drawing, in which

5 I have shown selected embodiments of the invention and in which:

Fig. 1 is a view of the top of a cap made according to my invention;

Fig. 2 is a section on the line 2—2 of Fig. 1
10 and showing one form which the invention may take;

Fig. 3 is a view on the same plane as Fig. 2
but on an enlarged scale and showing the parts
separated;

15 Figs. 4, 5, and 6 are views corresponding to Fig. 2 but showing other forms which the invention may take;

Fig. 7 is a sectional view of the three disks showing how they may be fastened together;

20 Fig. 8 is a view showing a still further embodiment.

Referring first to Figs. 1, 2, and 3, the cap is shown as having a wall 1 provided with threads adapted to engage the threaded neck of a bottle
25 to secure the cap in place. The cap is also provided with a top 2 which is continuous in this form so as to form, with the wall 1, a complete closure for the container to which the cap may be applied. I have omitted any showing of the
30 container as unnecessary to an understanding of the invention.

The top 2 is of substantial thickness, as indicated, and is shown as having therein a recess in the form of a circular groove 3. This groove
35 is preferably continuous and is adapted to receive downwardly extending flanges on one or more disks or pieces of sheet material. In the form shown in Figs. 1, 2, and 3, three such disks are shown, the bottommost one 4 being of metal,
40 the intermediate one 5 being of paper, and the uppermost one 6 being of celluloid or other transparent protective material. As best shown in Fig. 2, these disks have flanges 7, 8, and 9 which fit closely over one another and are received within
45 the groove 3. The groove is preferably formed in the molded material of the cap top, and then the flanges are inserted in the groove with a suitable adhesive, thus securing the sheets firmly in place on the cap.

50 In the form being described, the metal disk 4 closely fits the upper surface of the top 2 of the cap, so that it is uniformly engaged by the cap, and the paper disk may be used to carry any legend or illustration which, for example,
55 may be used to identify the contents of the con-

tainer on which the cap is placed. The celluloid disk 6 protects the paper and the legend or other data thereon.

While in Fig. 3 the several disks are shown as separated, they may be united before being attached to the cap and then the composite piece formed of three disks may be put in position and secured to the cap by inserting the three flanges in unison into the groove 3, preferably with a suitable adhesive to hold them there. Such an arrangement is indicated in Fig. 7, in which it will be seen that the flanges of the disks 5 and 6 are bent or crimped around the edge of the flange of the disk 4.

In Fig. 4 is shown a slightly different form 15 of the invention, except that in this instance the paper disk has been omitted. The legend or other identifying matter may be applied by suitable known processes directly to the surface of the metal, and then the protective covering of 20 celluloid may be put in place as before.

In Fig. 5 is shown still another form in which the metal disk is omitted, using only the paper and protective disks as before, while in Fig. 8 the metal disk is used alone and the data applied 25 directly to it.

In Fig. 6 is shown another form of the invention in which the wall 1 carries a top 2' having a central opening 10 therein, in this form surrounded by a downwardly extending flange 11. 30 Disposed in this opening is the head 12 of a rod 13, the opening and the head being shown as of wedged or conical shape so that the head cannot pass through the opening. The rod may be of any suitable form or material, and by the use of 35 the word "rod" I do not intend to limit myself to any particular shape thereof. This rod may, for example, be of glass or it may be the handle of a brush or any other suitable instrument for use with the contents of the particular bottle or other 40 container with which the cap is used, so that when the cap is removed, the instrument may be used to apply the contents of the bottle where desired.

The rod may have its head forced into engagement with the walls of the opening 10 and may 45 be further fastened in place by a suitable adhesive if so desired. In any case, it will be seen that the head cannot be moved downwardly, so that the rod 13 cannot be displaced into the 50 contents of the container. The upper surface of the head 12 preferably conforms to the surface of the top 2' and may be covered by a plurality of disks, as indicated, for example, in Figs. 2 and 3.

While I have shown the invention as embodied in certain specific forms, it is to be understood 55

that various changes in details may be made without departing from the scope of the invention, and I therefore do not intend to limit myself except by the appended claims.

5. I claim:

1. In combination, a cap adapted to close an opening in a container, means to secure said cap to said container, said cap having a continuous groove in the upper surface thereof, a piece of sheet material having a depending flange secured within said groove, said piece of sheet material being adapted to carry data thereon to identify the contents of the container, and a protective covering disposed over said piece of sheet material 10 and likewise extending into said groove.
2. In combination, a member having a continuous groove in a surface thereof, and a plurality of superimposed pieces of sheet material having depending flanges crimped together and secured within said groove, the topmost piece being of transparent protective material and the next 15 lower one carrying indicia thereon.
3. In combination, a cap adapted to close an opening in a container, means to secure said cap to said container, said cap having a continuous groove in the upper surface thereof, and three superimposed pieces of sheet material having depending flanges secured within said groove, the 20
- 25

lowermost piece being of metal, the intermediate piece being of paper having thereon data to identify the contents of the container, and the uppermost piece being of transparent protective material.

5

4. In combination, a cap adapted to close an opening in a container, means to secure said cap to said container, said cap comprising a top having an opening therethrough, a rod having a head disposed in said opening and larger than the 10 smallest dimension of the opening, whereby it cannot pass therethrough, and a piece of sheet material disposed on said top and extending over said head to conceal the same and secured to said top.

5. In combination, a cap adapted to close an opening in a container, means to secure said cap to said container, said cap comprising a top having an opening therethrough, a rod having a head disposed in said opening and larger than 20 the smallest dimension of the opening, whereby it cannot pass therethrough, and a plurality of superimposed pieces of sheet material extending over said head and concealing the same and secured to said cap, the topmost piece being of 25 transparent protective material, and the next lower one carrying identifying data thereon.

PHILIP O. HOAG.
